(57) CLAIM

The ornamental design for a pop-up flower bouquet with vase, as shown and described.

DESCRIPTION

FIG. 1 is a front top left side perspective view for a pop-up flower bouquet with vase, showing my new design; FIG. 2 is a front elevational view of FIG. 1 thereof; FIG. 3 is a rear elevational view of FIG. 1 thereof; FIG. 4 is a left side elevational view of FIG. 1 thereof; FIG. 5 is a right side elevational view of FIG. 1 thereof; FIG. 6 is an exploded front top left side perspective view of the pop-up flower bouquet with vase of FIG. 1, showing the flower bouquet and vase separated; FIG. 7 is a front top right side perspective view of the flower bouquet of the pop-up flower bouquet of FIG. 1 with vase shown separately for ease of illustration; and, FIG. 8 is an exploded rear top left side perspective view of FIG. 7.

The portions of the pop-up flower bouquet with vase shown in broken line form no part of the claimed design. The dash-dot-dash broken lines define the bounds of the claimed design and form no part thereof.

1 Claim, 8 Drawing Sheets
